CLAIM

I claim the ornamental design for an oval bottle, as shown and described.

DESCRIPTION

FIG. 1 is a perspective view of a bottle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portion of the pour spout shown in broken lines in the drawing views is included for the purpose of showing environmental structure that forms no part of the claimed design.
